CLAIM

We claim the ornamental design for a wireless communication base station, as shown and described.

DESCRIPTION

FIG. 1 is a front perspective view of a wireless communication base station of the present invention;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.

The broken line in FIG. 8 depicts a portion of the wireless communication base station that forms no part of the claimed design.

1 Claim, 8 Drawing Sheets
